(57) **CLAIM**

The ornamental design for a golf club locating device, as shown and described.

DESCRIPTION

FIG. 1 is a top and side perspective view of the golf club locating device showing my new design;

FIG. 2 is a bottom and side perspective view thereof;

FIG. 3 is a side view thereof, the opposite unshown side being of mirror image appearance;

FIG. 4 is a front view thereof;

FIG. 5 is a rear view thereof;

FIG. 6 is a top view thereof; and,

FIG. 7 is a bottom view thereof.

The broken line showing is included for the purpose of illustrating and forms no part of the claimed design.
